UNITED STATES PATENT OFFICE.

ADOLPH BAUMANN AND ABRAHAM SOMMERFELD, OF NEW YORK, N. Y.

GARBAGE-CAN.

1,158,958.

Specification of Letters Patent. Patented Nov. 2, 1915.

Application filed February 17, 1915. Serial No. 8,721.

To all whom it may concern:

Be it known that we, ADOLPH BAUMANN and ABRAHAM SOMMERFELD, citizens of the United States, and residents of the city of New York, State of New York, have invented certain new and useful Improvements in Garbage-Cans, of which the following is a full, clear, and exact specification.

Our invention relates particularly to ¹⁰ infecting receptacles for garbage.

The object of our invention is to provide a garbage can of simple and inexpensive construction having means for holding a disinfectant therein in such a manner that ¹⁵ the fumes of the disinfectant will thoroughly permeate the garbage whereby to deodorize the same and prevent breeding of insects or of vermin therein. According to our invention the can is constructed so that ²⁰ the disinfectant material and the holders thereof may be easily removed and replaced so as to facilitate charging the can with the disinfectant material and to permit of thoroughly cleaning the can and keeping it in ²⁵ a sanitary condition.

We attain the objects specified as well as others not herein enumerated by means of the device shown in the accompanying drawings, in which—

³⁰ Figure 1 is a vertical section of a garbage can embodying our invention. Fig. 2 is a transverse section on the line *aa* of Fig. 1, looking from the top and Fig. 3 is a plan of the inside of the cover, partly in section.

³⁵ Similar reference characters refer to similar parts throughout the several views.

Referring to the drawings, 1 indicates a garbage can which may be made of any suitable material and in any desirable form. ⁴⁰ The can is provided with a cover 2 for closing the open end thereof. In the interior of the wall of the can, and at the top and bottom thereof, are disposed a plurality of chambers, each of which contains a disinfectant material. Each of the wall chambers is formed by means of a bent perforated metal slide 3, the front and side portions of which are spaced from the wall of the can and are provided with perforations 4. A pair of slideways 5, suitably secured to the interior face of the wall of the can, is provided to hold each of the slides 3 in place. In the space between the wall of the can and the slide is contained a pad 6 ⁵⁵ made of felt or other suitable fibrous mate-

rial, which is saturated or impregnated with a suitable disinfectant. The top portion ⁷ of each of the slides 3 is made solid, that is without perforations, and is inclined upwardly toward the wall of the can, so as to ⁶⁰ prevent garbage from entering the disinfectant chambers.

At the bottom of the can is a circular perforated plate 8 having radial arms 9, which plate is detachably secured to the can by ⁶⁵ means of a bolt 10, or other suitable fastening element. Between the bottom of the can and the plate is contained a pad 6 saturated with disinfectant material similar to that heretofore described. ⁷⁰

The cover of the can is provided with a circular perforated plate 11 which is detachably secured thereto by means of a bolt ⁷⁵ 12, so that the said plate may be easily removed. In the space between the body of the cover 2 and the plate 11 is likewise contained a disinfectant pad 6.

From the foregoing description it will be seen that the disinfectant holders may be easily detached from the can so as to permit of thoroughly cleaning the same. ⁸⁰

When garbage has been placed in the can and the cover thereof closed, the fumes from the disinfectant material will escape through the perforations of the chambers ⁸⁵ holding the saturated pads, and will thoroughly permeate the contents of the can.

It will be understood that in practice changes in the specific construction shown may be made, and that any suitable materials and proportions may be used for the various parts, without departing from the spirit of the invention. ⁹⁰

What we claim is:

1. A garbage can having a plurality of ⁹⁵ perforated slides detachably secured to the inner wall thereof, and forming chambers for containing disinfectant material, a perforated plate having radial arms detachably secured to the bottom of the can, and disinfectant pads disposed between said plate and the bottom of the can, and also in the wall chambers, substantially as described. ¹⁰⁰

2. The combination with a garbage receptacle of a cover therefor, having a detachable perforated plate and a pad of disinfectant material disposed between the plate and the body of the cover, a bolt passing through the perforated plate and pad and threadedly engaged with the cover, a plu- ¹⁰⁵ ¹¹⁰

rality of vertical chambers within the body of the can and extending throughout the length thereof, said chambers having perforated front and sides, and being solid at the top, and a pad of disinfectant material contained in each of said chambers substantially as described.

In testimony whereof, we have hereunto

affixed our signatures in the presence of two subscribing witnesses.

ADOLPH BAUMANN.
ABRAHAM SOMMERFELD.
